FIXTURE FOR TAPING FOLDED NEWSPAPERS
Carroll E. Smith, 2336 Graydon, Monrovia, Calif.
Filed Sept. 8, 1964, Ser. No. 394,663
4 Claims. (Cl. 225—77)

The present invention relates generally to tape dispensers and particularly to a dispenser for dispensing and applying pressure sensitive tape.

In its broader aspects, the invention provides a tape dispenser which is uniquely constructed and arranged to permit a length of pressure sensitive tape to be applied about or wrapped around an article by grasping the article in one hand, engaging the article with the free end of the tape, and moving the article in a prescribed arcuate path of movement relative to the dispenser. During the terminal motion of the article, the tape is engaged with a cutter on the dispenser which severs the length of applied tape from the tape roll on the dispenser.

A particularly useful application of the dispenser involves the home delivery of newspapers by a delivery boy on a bicycle. Thus, it is common practice for a delivery boy to deliver newspapers to the homes along his route by folding the newspapers and throwing them into the customers' yards as he rides along the route on a bicycle or in an automobile. To enable the papers to be thus thrown without scattering, the folded papers are secured in some fashion to prevent them from unfolding as they travel through the air. In some cases, for example, the edges of the folded papers are interleaved in a manner which retains the papers in their folded condition. In other cases, the folded papers are enclosed in a wrapper or encircled by a rubber band. These methods of securing the folded papers, however, require the use of two hands, thereby precluding the delivery boy from securing the folded papers as he rides along his route.

The present invention provides a tape dispenser which may be mounted on the handle bar of a bicycle and which permits a newspaper delivery boy to wrap a length of pressure sensitive tape about folded newspapers with one hand as he rides along his route, steering the bicycle with the other hand. The overall time consumed in folding, securing, and delivering the newspapers is thereby substantially reduced. While the dispenser is particularly adapted for installation on a bicycle, it may be mounted on a stationary support or in an automotive vehicle. Moreover, while the dispenser is intended primarily for applying pressure sensitive tape about folded newspapers, it may be used for other purposes.

It is therefore a general object of the present invention to provide a novel tape dispenser of the character described.

A more specific object of the invention is the provision of a tape dispenser which permits a length of pressure sensitive tape to be applied about an article with one hand.

An object of this invention is to provide a tape dispenser which is particularly adapted for installation on a bicycle to permit a newspaper delivery boy to apply pressure sensitive tape about folded newspapers as he rides along his route, thereby to permit such papers to be thrown without scattering.

A further object of the invention is to provide a tape dispenser which is relatively simple in construction, economical to manufacture, easy to use, and otherwise ideally suited to its intended purposes.

Other objects, features and advantages of the present invention will become apparent to those versed in the art from a consideration of the following description,

the appended claims and the accompanying drawings, wherein:

FIGURE 1 is a perspective view of a dispenser according to the present invention installed on a bicycle;

FIGURE 2 is an enlarged perspective rear view of the dispenser of FIGURE 1;

FIGURE 3 is a sectional view taken at line 3—3 of FIGURE 2;

FIGURE 4 is an enlarged sectional view taken at line 4—4 in FIGURE 3;

FIGURE 5 is an enlarged sectional view taken at line 5—5 of FIGURE 2;

FIGURE 6 is an enlarged sectional view taken along line 6—6 in FIGURE 3; and

FIGURE 7 is an exploded perspective view of the parts shown in FIGURE 6.

The illustrated tape dispenser 10 comprises supporting means including a tape support 12 in the form of a rectangular channel having downwardly directed side walls 14 joined along their upper edges by a connecting top wall 16. Rigidly secured to the tape support 12, generally centrally of its ends, are a pair of L-shaped supporting arms 18. These supporting arms include relatively short, normally horizontal ends 20 which project forwardly from the forward side wall 14 of the tape support 12 and relatively long, normally vertical ends 22 which depend a distance below the support. On the lower extremities of the supporting arms 18 are clamps 24 for securing the supporting arms to a supporting base which is shown to be the handle bar 25 of a bicycle. FIGURE 5 illustrates one of these clamps in enlarged detail. Referring to this latter figure, each clamp 24 will be seen to comprise an upper clamp member 26 including an enlargement 28 having a bore 30 and a clamp arm 32 extending from the upper end of the enlargement 28, generally normal to the axis of the bore 30. Each clamp 24 further includes a lower clamp member 34 which straddles the lower end of the enlargement 28 and is pivotally attached to the enlargement by a pivot pin 36. Lower clamp member 34 has clamp arms 38 extending in the same direction as the upper clamp arm 32 and spaced from the latter arm to receive the handle bar 25 therebetween.

The outer ends of the lower clamp arms 38 are joined by a cross pin 40. Rotatably mounted on this cross pin is a sleeve 42 from which extends a transverse threaded shaft or bolt 44. The outer end of the bolt 44 is receivable within a slot 46 in the upper clamp arm 32 and mounts a wing nut 48 which may be tightened to draw the clamp arms 32, 38 toward one another, thereby to secure the clamp 24 to the handle bar 25. Preferably, the clamp arms 32 and 38 have resilient inserts 50 and 52, respectively, engageable with the handle bar 25 for providing effective frictional contact between the clamp and handle bar.

Bore 30 in each clamp 24 is proportioned to slidably receive the lower end 22 of its respective clamp arm 18. Each clamp is adjustably secured to its respective supporting arm by a thumb screw 54. At this point, therefore, it is apparent that the tape dispenser 10 is secured to a bicycle by attaching the clamps 24 to the handle bar 25 of the bicycle, inserting the supporting arms 18 through the clamp bores 30, and tightening the thumb screws 54 against the supporting arms. The elevation of the tape support 12 is simply adjusted by releasing the screws 54.

Mounted on the under side of the housing 12, adjacent the left hand end thereof, as the housing is viewed in FIGURES 2 and 4, are means 56 for rotatably mounting a supply roll 58 of the pressure sensitive tape 60 to be dispensed. The tape roll mounting means 56 comprises a pair of support arms 62 which are rigidly secured, as

by welding, to the inner surfaces of the tape support side walls 14 and depend a distance below the support. Adjacent their lower ends, the arms 62 have transverse slots 64 opening through their left hand edges, as the arms 64 are viewed in FIGURES 4, 6 and 7. Along their right hand edges, the arms have upwardly presented shoulders 66 located a distance above the slots 64. Arms 62 rotatably support the ends of a shaft 68 which extends across the space between the arms. To this end, the shaft 68, which is somewhat larger in diameter than the width of the slots 64, is circumferentially grooved adjacent its ends at 70 to rotatably fit in the slots. The side walls of the grooves 70 define axially facing shoulders on the shaft engageable with the support arms 62 at opposite sides of the slots 64 to retain the shaft axially. The tape roll 58 is disposed between the support arms 62 and has a central opening 72 which loosely receives the shaft 68, whereby the tape roll is rotatably held by the tape roll mounting means 56.

Slidable on each support arm 62 is a shaft retainer 74. Each retainer 74 comprises a generally L-shaped member with angularly disposed legs 78 and 80. Extending through each retainer 74, parallel to the retainer leg 80, is a rectangular slot 82. The upper end of this slot opens through the upper surface of and is bounded on all four sides by the leg 78 of the retainer. The lower end of the slot opens through the inner and lower edges of the retainer leg 80. The retainers 74 are slidably positioned on the support arms 62 above the shoulders 66. Accordingly, the retainers are movable downwardly along the support arms 62 to lower limiting positions wherein the retainer legs 78 seat against the support arm shoulders 66. When in these lower limiting positions, the retainer legs 80 extend downwardly across the open ends of the support arm slots 64 to retain the tape roll shaft 68 in the support slots. The shaft 68 may be removed from the support arms, to permit replacement of the tape roll, by sliding the retainers 74 upwardly to clear the support arm slots.

Rigidly joined, as by welding, to the inner surfaces of the tape support side walls 14, approximately between the ends of the support, are a pair of support arms 84 which also depend below the support. Disposed between and rotatably supported on the lower ends of these arms is a tape positioning means, shown to be a roller 86. As shown best in FIGURE 4, a depending length of the tape 60 is trained around and hangs vertically from the roller 86.

Rigidly mounted on the under side of the tape support 12, at the end thereof, remote from the tape roll 58, is a tape cutter 88. This cutter is shown to comprise a blade which extends between and is rigidly joined, as by welding, to the inner surfaces of the housing side walls 14. The cutting edge of the blade extends along the lower edge of the blade.

In use of the dispenser 10, the depending length of the tape 60 is trained about the roller 86 and normally hangs downwardly therefrom. Preferably, the lower extremity of the tape is anchored by temporary attachment to a tape anchor on the dispenser base. In the drawings, for example, the lower extremity of the tape is pressed against the underlying frame member 90 of the bicycle, in the manner shown in FIGURE 2, which frame member, then forms a tape anchor. To this end, the dispenser 10 is mounted on the handle bar 25 of the bicycle in a position wherein the dispenser roller 86 is located over the frame member 90. When applying the tape 60 to a folded newspaper, the latter is grasped with one hand and pressed against the adhesive side of the tape 60 in the manner illustrated in solid lines in FIGURE 2. Thereafter, the paper is moved in a generally circular path, upwardly and toward the end of the tape support 12 mounting the cutter 88, and the paper is simultaneously rotated to wrap the tape about the paper, as shown in phantom lines in FIGURE 2. This motion of the paper is carried out in such manner that the paper is moved from its initial position I,

through an intermediate position II, to a final position III, wherein the paper is located just beyond the cutter end of the tape support 12 and the tape 60 engages the cutter 88 just beyond the edge of the folded paper, thereby to sever the length of tape about the paper from the supply roll. The folded paper may now be thrown from the bicycle, while in motion, without scattering of the paper. The dispenser is conditioned for reuse by pressing the free end of the tape against the bicycle frame member 90, as explained earlier. It is apparent that the operations described above may be carried out by a delivery boy on the bicycle using one hand, thereby leaving the other hand free to steer the bicycle.

As explained earlier, while the present dispenser 10 is particularly adapted for installation on a bicycle, it may be installed on an automotive vehicle or on a stationary support, if desired. Moreover, the tape dispenser may obviously be used for purposes other than applying pressure sensitive tape to newspapers.

It is evident at this point that the invention provides a tape dispenser having a base, which in the illustrated embodiment of the invention is a bicycle, a tape support including means 56 for rotatably mounting a supply roll of pressure sensitive tape in such manner that a substantial clearance space is provided between the base and the tape support and supply roll, tape positioning means 86 on the tape support for supporting and positioning a depending length of the pressure sensitive tape to hang downwardly below the support and supply roll into the clearance space between the support and the dispenser base, the tape anchor on the base below the tape positioning means for temporary attachment to the free or lower extremity of the depending tape length, and a cutter on the tape support. The tape dispenser is constructed and arranged in such a way that a depending length of tape is disposed for application to an article, such as the illustrated folded newspaper, by initial movement of the article through the clearance space between the dispenser base and tape support into adhesive contact with the adhesive surface of the depending tape length and subsequent upward arcuate movement of the article through the clearance space in simultaneous rotation of the article to wrap the depending tape length about the article. During this application of the tape to the article, the depending tape length swings upwardly in a generally vertical plane normal to the plane of the depending tape length and toward the tape support 12 to a final position of severing engagement with the tape cutter 88. It is significant to note that the supporting members 22 which mount the tape support 12 on the dispenser base are laterally offset from this plane of swinging movement of the depending tape length in such manner that these supporting members do not obstruct the clearance space between the base and tape support and thus do not inhibit movement of the article being taped through the clearance space in the manner just explained.

Those versed in the art will appreciate that the present invention achieves the objects and realizes the advantages hereinbefore mentioned.

Although a specific embodiment of the present invention has been illustrated and described herein, it will be understood that the same is merely exemplary of presently preferred embodiments capable of attaining the objects and advantages hereinbefore mentioned, and that the invention is not limited thereto; variations will be readily apparent to those versed in the art, and the invention is entitled to the broadest interpretation within the terms of the appended claims.

The inventor claims:

1. In combination, supporting means for rotatably mounting a roll of pressure-sensitive tape in an elevated position on a supporting structure, positioning means for mounting a depending length of said tape to hang downwardly, a cutter spaced from the positioning means, and means connected with the supporting means and beneath the positioning means for attachment of the depending

tape portion thereto to temporarily secure the tape portion and to present resistance to pressure against said tape portion to secure said tape portion to an article to be taped to facilitate attachment of the tape to the article.

2. A tape dispenser for applying pressure sensitive tape to an article, comprising: a base, a tape support disposed a distance above said base, means on said support for rotatably mounting a supply roll of pressure sensitive tape in such manner as to provide a substantial clearance space between said base and said tape support and supply roll, 10 tape positioning means on said tape support for supporting and positioning a depending length of said tape to hang downwardly below said support and supply roll into said clearance space, whereby said depending tape length is disposed for application to said article by initial movement of 15 said article through said clearance space into adhesive contact with the adhesive surface of said tape length and subsequent upward arcuate movement of said article through said clearance space and simultaneous rotation of said article in such manner as to wrap said depending tape length 20 about said article and swing said depending tape length upwardly in a generally vertical plane normal to the plane of said tape length and toward said tape support, a cutter mounted on said tape support for severing engagement with said depending tape length during said upward swing- 25 ing movement of said tape length, a supporting member mounting said tape support on said base, and said supporting member being disposed in laterally offset relation to said clearance space so as to not obstruct said clearance space nor inhibit movement of said article through said 30 clearance space.

3. A tape dispenser according to claim 2 including tape anchor means on said base below said tape positioning means for attachment to the lower extremity of said depending tape length, thereby to temporarily secure said 35 tape length against swinging movement and thus facilitate initial adhesive contact of said article with the adhesive surface of said tape length.

4. A tape dispenser for applying pressure sensitive tape to an article, comprising supporting means including a tape 40 support and a tape anchor means disposed in spaced relation so as to define therebetween a substantial clearance space, means on said tape support for rotatably mounting a supply roll of pressure sensitive tape, tape positioning means on said support for supporting and positioning a 45 free length of said tape in a position wherein the free ex-

tremity of said tape length may be temporarily attached to said anchor means, whereby said tape length is disposed for application to said article by initial movement of said article to said clearance space into adhesive contact with the adhesive surface of said tape length and subsequent arcuate movement of said article through said clearance space toward said tape support and simultaneous rotation of said article in such a way as to wrap said tape length about said article and swing said tape length toward said tape support, and a cutter mounted on said tape support for severing engagement with said tape length during said swinging movement thereof.
